(57) CLAIM

The ornamental design for a hitch cover, as shown and described.

DESCRIPTION

FIG. 1 is a perspective view of the hitch cover in full lines with a plug shown in broken lines in FIGS. 1, 3-7 representing environmental association matter being for illustrative purposes only and forming no part of the claimed invention.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view of the hitch cover; and,

FIG. 7 is a bottom plan view thereof.
